TELLTALE SYSTEM FOR ELECTRIC CIRCUITS.

1,134,435.

Specification of Letters Patent.

Patented Apr. 6, 1915.

Application filed November 13, 1914. Serial No. 871,979.

To all whom it may concern:

Be it known that I, CLARENCE E. BEACH, a citizen of the United States, residing at Binghamton, in the county of Broome and 5 State of New York, have invented a new and useful Telltale System for Electric Circuits, of which the following is a specification.

This invention relates to telltale systems which are particularly applicable to signaling systems such as are adapted, for example, to the protection of factory premises, and in which it is desirable to provide a telltale by means of which the running down 10 or breaking of the motor spring of any electromechanical device, such as a gong or a register, may be immediately indicated at some central point, so that steps may be taken to put such device back into service.

An object of this invention is to provide 20 for such a telltale system by the use of a minimum amount of wiring.

Another object of this invention is to provide such a telltale system wherein the contacts will be maintained under constant test 25 without the use of any separate source of energy.

Another object of this invention is to provide such a telltale system in which the failure of any telltale contact will not disable any part of the signaling system.

Another object of this invention is to provide for the use of such a telltale in connection with a system adapted to the use of electromechanically actuated devices which 35 require a comparatively large electric current for their control, while maintaining a constant test of the continuity of the circuit with a comparatively small current.

This invention contemplates a utilization 40 of two conductors either of which is adapted to act as a return between one terminal of the current source and all of the transmitting devices and receiving devices, said conductors being jointly used as a return during 45 one condition of the telltale contacts, and but one of said conductors being employed as a return during another condition of said telltale contacts. Such wiring is so utilized by providing an indicating device and a resistance or counter electromotive force, so connecting them to the return conductors that there will normally be a sufficient difference of potential at the terminals of the indicating device to effectively energize it, 50 and so connecting the telltale contacts with

said return conductors that the operation of said contacts will deenergize said indicating device.

For the purpose of more clearly illustrating the construction and operation of this 60 telltale system, the accompanying drawing shows the manner of its application to different types of signaling systems, one type comprising an ordinary series signaling circuit, and the other being arranged in accordance with the invention shown and more 65 fully described in my copending application, Serial No. 839,849.

In the accompanying drawing in which like characters of reference refer to similar 70 parts throughout: Figure 1 shows a typical series signaling circuit with this invention applied thereto. Fig. 2 shows this invention applied to a particular type of signaling circuit, to be described.

Referring to Fig. 1, three signaling stations A, B and C are shown, connected by the outgoing wire 1, and the return wires 2 and 3 to the source 5.

Typical transmitting devices are shown at 80 each of the signaling stations, including the signal wheel 8, the signaling lever 9, the contacts 10 and 11, together with the non-interference magnet 12, and the armature structure 13 controlled thereby, said armature 85 structure acting in a well known manner to hold the signaling lever in closed circuit position whenever the magnet 12 becomes deenergized when the associated contacts 10 and 11 are closed.

At each of the stations a signal receiving device may be installed, here indicated as electromechanical gongs 6, the transmitting devices and said gongs being serially connected in the wire 1.

The trouble magnet 14 is equipped with contacts to close the circuit of a trouble bell 19 whenever said magnet is deenergized, and said magnet is connected between the return wires 2 and 3 at one end thereof, while a 100 resistance or counter electromotive force 15 (which, for the sake of brevity, I will hereinafter refer to as a resistance) is connected between said return wires at the other end thereof. Under normal conditions, sufficient 105 current is caused to pass through magnet 14, in parallel with resistance 15, to energize said magnet, and the resistance 15 must be so low that the operation of the system will not be impaired if the wire 2 is broken.

105

110

The gongs 6 are provided with normally closed telltale contacts 7, which are operated by the motor spring or by any suitable part of the gong mechanism, to indicate when the 5 device has run down, or otherwise needs attention.

The contacts 7 are connected in series in wire 2, and since the details of construction and mounting of such telltale contacts are 10 well known in the art, it is thought not necessary to confuse the drawing by showing such details therein. The telltale contacts may be connected between wires 2 and 3, as shown at station A' in Fig. 2, but it is preferable 15 to connect such contacts in the manner shown in Fig. 1 so that said contacts, and their effectiveness, may be kept under constant test. In general, the telltale contacts 7 should be connected to such wires of 20 any system that no portion essential to the operation of any transmitting or receiving devices can be disabled by the operation of any or all of said contacts.

The current normally flows through the 25 system shown in Fig. 1 as follows: from the upper terminal of source 5, through outgoing wire 1 and the gongs 6 and contacts 10 and 11 and magnet 12 at stations A, B and C, which are serially included therein, to one terminal of resistance 15, where the 30 current divides,—part of the current flowing through said resistance 15 and return wire 3 to the other terminal of source 5,—the remainder of the current flowing 35 through return wire 2 and the contacts 7 of the stations C, B and A serially included therein, and magnet 14 to the return wire 3 where it joins the path from resistance 15 to the other terminal of source 5. The current 40 normally flowing through wire 1 is sufficient to energize all of the electromagnets included therein, and the portion of the current flowing through wire 1 which normally passes through wire 2 is sufficient to effectively energize the electromagnet 14 to hold the circuit of bell 19 open.

The operation of the system shown in Fig. 1 will now be described. Any signal 50 wheel 8 is operated to break and close the circuit at the contacts 10 and 11 associated therewith. The gongs 6 and magnets 12 are affected by such breaks and closures in a typical well known manner. Thus at every 55 break in the current flow in wire 1, a tap will be sounded on the gongs 6 and the armatures of the non-interference magnets 12 will be released. In the event of an accidental break in wires 1 or 2, magnet 14 will permit the circuit of bell 19 to be closed. 60 If the spring of any gong 6 runs down, to such an extent as to operate its associated telltale contacts 7 to open the circuit through wire 2, magnet 14 will thereupon fail and cause the operation of bell 19.

65 Fig. 2 shows a trouble magnet 14', a

source of energy 5', and signaling stations A', B' and C', having transmitting devices and gongs, all of which are similar to corresponding parts shown in Fig. 1. The transmitting devices are serially connected 70 in the wire 1', and the gongs are serially connected in the wire 4, the wires 2' and 3' being adapted to act as a return between one terminal of the current source 5' and all of said transmitting and receiving devices 75 under certain conditions hereinafter referred to, and under other conditions forming a part of a return current path, in parallel with the resistance 15', for the current flowing from wire 1' to said terminal of 80 the current source through wire 4. The trouble magnet 14' is connected between return wires 2' and 3' at one end thereof, while resistance or counter electromotive force 15' is connected between said wires at 85 the other end thereof, and thus provides for the effective operation of the signaling system in case wire 2 is open, and when said wire 2 is closed, and normal line current is flowing, sufficient current is caused to pass 90 through the magnet 14', in parallel with resistance 15', to energize said magnet. The contacts 7' of the gongs 6' may preferably be normally closed, as shown at stations B' and C', or may be normally open, as shown 95 at station A'. The contacts 7' of stations B' and C' are connected in series in return wire 2', while the contacts 7' of station A' are connected between the return wires 2' and 3'.

Relay 16 controls the contacts 20 and 21, contact 20 being adapted to connect one terminal of source 5' to wire 3', and contact 21 being adapted to connect the other terminal of source 5' to wire 4, whenever relay 16 is deenergized. This relay and the resistance 17 are connected between one end of wire 1' and one terminal of source 5', while resistance 18 is connected between one end of wire 4 and the other terminal of source 5'. Resistances 17 and 18 are provided to avoid useless expenditure of energy, the resistance of said circuit being so high that the magnets of gongs 6' are normally not effectively energized, and, as relay 16 and resistance 17 are momentarily connected 105 directly across source 5', in parallel with resistance 18, when contacts 20 and 21 are closed, it is desirable that the resistance of these paths should be equal, in order to reduce to a minimum the waste current there-through. Condenser 22 is connected between wires 3' and 4 to decrease the spark at contacts 20 and 21.

Keys 23, 24 and 25 and resistances 26 and 27 may be provided so that the location of any particular trouble may be ascertained by operating these keys and noting the effect thereof upon magnet 14', or, in place of said keys and resistances, additional trouble magnets may be provided for controlling 115 120 125 130

suitable trouble indicating devices to designate the portion of the circuit affected, in any well known manner.

By connecting all of the signal transmitting devices in the wire 1', and all the signal receiving devices in the wire 4, the wires 2' and 3' are available for use both to complete the circuit for these devices and also for the purposes of the "telltale" system, as 10 will be hereinafter more fully explained.

Current normally flows through the system as follows: from upper terminal of source 5' through resistance 17, relay 16, to wire 1', through contact 10', contact 11', 15 and magnet 12' at stations A', B' and C', through wire 2', contacts 7' at stations C' and B' to key 24, magnet 14', wire 3', to wire 4, through gongs 6' at stations C', B' and A', to resistance 18, to the other side of source 5'. Current also flows from wire 2' to wire 3' through resistance 15'. The current normally flowing through the wires 1', 2', 3' and 4 is sufficient to energize all of the electromagnets therein except the magnets 25 of gongs 6' which are normally not effectively energized.

The operation of the embodiment of this invention shown in Fig. 2 is the same as that illustrated in Fig. 1 except in the following respects. When the circuit is opened and closed at contacts 10' and 11' of any signaling station, relay 16 responds to the break by releasing its armature to close its contacts 20 and 21. Whenever these contacts 30 are closed, the following circuit is established: from upper terminal of source 5' to contact 21, to wire 4, dividing into two branches; (1) through wire 4 and gongs 6', to wire 3', contact 20 to lower terminal of source 5'; (2) through resistance 18 to lower terminal of source 5'. Now, when contacts 10' and 11' are closed, the following third path is established: from upper terminal of source 5', through resistance 17, 35 relay 16, wire 1' to one terminal of resistance 15' where the current divides,—part of the current flowing through said resistance 15' and return wire 3' and contact 20, to lower terminal of source 5',—the remainder of said current flowing through return wire 2' and the contacts 7' of the stations C' and B' serially included therein, and magnet 14' to return wire 3', where it joins the path from resistance 15' to the 40 other terminal of source 5'. It will be noted that this third path is closed only while the contacts 10', 11' and 20 are simultaneously closed.

While the contacts 20 and 21 are closed, 45 the current through gongs 6' is reversed and greatly increased, and the magnets of these gongs are effectively energized and attract their armatures to release their striking mechanism. The reversal of the current through these magnets when contacts 20

and 21 are again opened overcomes any residual magnetism which might be present and which might tend to hinder the operation of the gongs. At every break in the wire 1' a tap will be sounded on the gongs 6'. 70

The deenergization of magnet 14' in the event of an accidental break in any of the wires 1', 2', 3' or 4, while the contacts 20 and 21 are open, will cause the trouble bell 19' to sound. 75

If the spring of the gong 6' at either station B' or C' is run down, to such an extent as to operate the contacts 7' thereat to open wire 2', magnet 14' will thereupon fail and cause the operation of trouble bell 19'. If it is desired to have the contacts 7' stand normally open, and connected as shown at station A', the operation of these contacts will be to short circuit the magnet 14', to cause it to release its armature. 80

If either of the wires 1' or 4 should break, both magnet 14' and relay 16 will fail. If the break is in wire 1', the pressing of key 23 will result in the energization of both magnet 14' and relay 16. If the break is in wire 4, it will require the pressing of key 25 to result in the energization of both magnet 14' and relay 16. If either wire 2' or 3' should break, only magnet 14' will fail. If the break is in wire 2', the pressing of key 23 will result in the energization of magnet 14'. If the break is in wire 3', it will require the pressing of key 25 to result in the energization of magnet 14'. 90

The continuity of resistance 15' may be 100 tested by use of the key 24. If the circuit through this resistance is continuous, the pressing of this key will result only in the failure of magnet 14', while if the circuit through this resistance is open, the pressing 105 of the key 24 will also result in the failure of relay 16.

While "non-interfering" signal transmitting devices are shown, it is obvious that either "plain" or "succession" devices may 110 be used if desired.

The foregoing applications of this invention are typical, and the invention may be correspondingly applied to other systems. I therefore do not wish to limit myself to 115 the particular construction shown and described, as changes may be made therein without departing from the spirit of this invention.

The signaling system shown in Fig. 2 and 120 hereinbefore described in connection with said figure is not herein claimed, as the same forms the subject matter of another application filed by me, Serial No. 839,349.

What I claim and desire to secure by Letters Patent of the United States is:

1. In a signaling system: a circuit including a source of energy, a resistance, transmitting devices, and receiving devices; a shunt for a portion of said circuit including 125

said resistance and no transmitting devices or receiving devices; an indicating device in said shunt; and means controlled by each of several of said receiving devices for controlling the operation of said indicating device.

2. In a signaling system: a source of energy; a resistance; transmitting devices; receiving devices; conductors operatively connecting said source, said resistance, said transmitting devices, and said receiving devices; said resistance being connected in the current path between a terminal of said source and said receiving devices; a shunt for said resistance including an indicating device; and mechanism associated with each of several of said receiving devices for suitably controlling said shunt.

3. In a signaling system: a source of energy; a resistance; transmitting devices; receiving devices; conductors operatively connecting said source, said resistance, said transmitting devices, and said receiving devices; said resistance being connected in the current path between a terminal of said course and said receiving devices; a shunt for said resistance including an indicating device; and mechanism associated with each of several of said receiving devices for controlling the continuity of said shunt.

4. In a signaling system: a source of energy; a resistance; transmitting devices; normally wound receiving devices; conductors operatively connecting said source, said resistance, said transmitting devices, and said receiving devices; said resistance being connected in the current path between a terminal of said source and said receiving devices; a shunt for said resistance including an indicating device; and mechanism operated by the running down of any of several of said receiving devices for suitably controlling said shunt.

5. In a signaling system: a source of energy; a resistance; transmitting devices; normally wound receiving devices; conductors operatively connecting said source, said resistance, said transmitting devices, and said receiving devices; said resistance being connected in the current path between a terminal of said source and said receiving devices; a shunt for said resistance including an indicating device; and mechanism operated by the running down of any of several of said receiving devices for controlling the continuity of said shunt.

6. In a signaling system: a circuit including a source of energy, transmitting devices, normally wound receiving devices, and two conductors either of which is adapted to act as a return between one terminal of said source and all of the transmitting devices and receiving devices; an indicating device connected between one end of one of said conductors and one end of the other of said conductors; and means operated by the run-

ning down of any of several of said receiving devices for breaking one of said conductors.

7. In a signaling system; a circuit including a source of energy, transmitting devices, normally wound receiving devices, and two conductors either of which is adapted to act as a return between one terminal of said source and all of the transmitting devices and receiving devices; an indicating device connected between one end of one of said conductors and one end of the other of said conductors; a resistance connected between the remaining ends of said conductors; and means operated by the running down of any of several of said receiving devices for breaking one of said conductors.

8. In a signaling system; a circuit including a source of energy, a plurality of transmitting devices, a plurality of receiving devices, each comprising a spring driven electromechanical gong having a circuit controller controlled by the running down or winding up of the spring of said gong, and two conductors either of which is adapted to act as a return between one terminal of said source and all of the transmitting devices and receiving devices; and an indicating device connected between one end of one of said conductors and one end of the other of said conductors; several of said circuit controllers being arranged to suitably control said indicating device without operatively affecting the control of said receiving devices by said transmitting devices.

9. In a signaling system; a circuit including a source of energy, a plurality of transmitting devices, a plurality of receiving devices, each comprising a spring driven electromechanical gong having a circuit controller controlled by the running down or winding up of the spring of said gong, and two conductors either of which is adapted to act as a return between one terminal of said source and all of the transmitting devices and receiving devices; an indicating device connected between one end of one of said conductors and one end of the other of said conductors; and a resistance connected between the remaining ends of said conductors; several of said circuit controllers being arranged to suitably control said indicating device without operatively affecting the control of said receiving devices by said transmitting devices.

10. In a signaling system, a resistance and a plurality of transmitting devices in one wire thereof, a resistance and a plurality of receiving devices in another wire thereof, an indicating device so associated with other wires of said system that the operation of said device may be controlled without affecting the operation of the rest of the system, means for so controlling the operation of said indicating device, and means con-

trolled by any transmitting device for connecting said resistances in multiple with each other and with the receiving devices.

11. In a signaling system, a resistance and 5 a plurality of transmitting devices in one wire thereof, a resistance and a plurality of receiving devices in another wire thereof, an indicating device and a third resistance connected in multiple at opposite ends of other 10 wires of said system, means connected with said other wires for controlling the operation of said indicating device, and means controlled by any transmitting device for connecting said first named resistances in 15 multiple with each other and with the receiving devices.

12. In a signaling system, a resistance and 10 a plurality of transmitting devices in one wire thereof, a resistance and a plurality of receiving devices in another wire thereof, an indicating device and a third resistance connected in multiple at opposite ends of other 15 wires of said system, means connected with said other wires for controlling the operation of said indicating device, and means controlled by any transmitting device for connecting said other resistances in multiple with each 20 other and with said receiving devices.

25

connecting said first named resistance, said transmitting devices and said indicating device and third resistance in multiple with the second named resistance and with the receiving devices. 30

13. In a signaling system, a metallic circuit, a plurality of transmitting devices in one wire thereof, a plurality of receiving devices in another wire thereof, an indicating device and a resistance connected in multiple at opposite ends of other wires of said circuit, means connected with said other wires for controlling the operation of said indicating device, a source of energy for 40 said circuit, two other resistances normally in series therewith, and means controlled by any transmitting device for connecting said other resistances in multiple with each other and with said receiving devices. 45

In witness whereof I have hereunto subscribed my name this 12th day of November, A. D. 1914.

C. E. BEACH.

It is hereby certified that in Letters Patent No. 1,134,435, granted April 6, 1915, upon the application of Clarence E. Beach, of Binghamton, New York, for an improvement in "Telltale Systems for Electric Circuits," errors appear in the printed specification requiring correction as follows: Page 4, line 25, for the word "course" read *source*; same page, line 98, for the word "indicatng" read *indicating*; and that the said Letters Patent should be read with these corrections therein, that the same may conform to the record of the case in the Patent Office.

Signed and sealed this 4th day of May, A. D., 1915.

[SEAL.]

R. F. WHITEHEAD,

Acting Commissioner of Patents.
